[57] CLAIM

The ornamental design for a nail clipper, as shown and described.

DESCRIPTION

FIG. 1 is a right side elevational view of a nail clipper embodying my design the left side being a mirror image thereof;

FIG. 2 is a top plan view thereof;

FIG. 3 is a bottom plan view thereof;

FIG. 4 is a front elevational view thereof;

FIG. 5 is a back elevational view thereof;

FIG. 6 is a cross-sectional view thereof, taken along the line 6—6 of FIG. 2; and,

FIG. 7 is a right side elevational view thereof, showing the design of FIGS. 1-6 in an alternative configuration, the left side being a mirror image thereof.
